UNITED STATES PATENT OFFICE.

SAMUEL KAPLAN, OF MONROE, LOUISIANA.

WHEEL.

Application filed December 1, 1924. Serial No. 753,282.

To all whom it may concern:

Be it known that I, SAMUEL KAPLAN, a citizen of the United States, and a resident of Monroe, Ouachita Parish, Louisiana, have invented a new and useful Improvement in Wheels, of which the following is a full, clear, and exact description.

My invention relates to improvements in wheels, and it consists in the combinations, 10 constructions, and arrangements herein described and claimed.

An object of my invention is to provide an improvement over that form of the device shown in my co-pending application for 15 wheel, Serial No. 282,835, filed August 18, 1924. In said co-pending application I showed a device in which the rim could be positively moved into locking engagement with the felly of the wheel, and positively 20 loosened from the felly, these two operations being accomplished by a single bolt. I further showed novel means for wedging the rim to the felly at various places, where- 25 by the felly could be readily secured to the rim.

The principal object of the present application is to construct the means for securing the rim to the felly in such a manner that the rim, although rigidly secured to the de- 30 vice, will not be so fastened to the felly that it cannot be readily released from the felly.

A further object of my invention is to provide a wheel in which the felly has novel means for engaging with both sides of the 35 rim so as to provide a large supporting surface for the rim.

A further object of my invention is to provide a wheel which is extremely simple in construction, positive in operation, and 40 which is durable and efficient for the purpose intended.

Other objects and advantages will appear in the following specification, and the novel features of the invention will be particularly 45 pointed out in the appended claims.

My invention is illustrated in the accom- 50 panying drawings, forming part of this application, in which—

Figure 1 is a plan view of a portion of 50 the felly,

Figure 2 is a side elevation of Figure 1,

Figure 3 is a section substantially along the line 3—3 of Figure 2,

Figure 4 is a plan view of another portion of the felly,

Figure 5 is a side elevation of Figure 4,

Figure 6 is a section along the line 6—6 of Figure 5, and

Figure 7 is a section through a modified form of the device.

In carrying out my invention I provide a felly which in the present instance is constructed of metal and which is provided with a cylindrical portion 1, (see Figure 6) and outwardly extending flanges 2 and 3. 65 The felly is mounted upon spokes 4 and is provided with openings 5 in which the free ends of the spokes 4 are received. It will be noted from Figures 1 and 6 that the flanges 2 and 3 are bent inwardly at 6 and 7 so as 70 to provide inclined surfaces for a purpose hereinafter described. It will also be noted that the sides 2 and 3 and the inclined surfaces 6 and 7 act as reenforcing means for the felly.

The means for locking the rim 8 to the felly consists in a locking plate 9 and locking projections 10. I have found that three or four projections 10 spaced equally about the rim are sufficient for locking the rim to 80 the felly.

Figures 1 to 3 inclusive clearly show the locking plate 9 while Figures 4 to 6 inclusive show one of the locking projections 10.

I will now define the specific construction of the rim locking plate 9. In Figure 2 it will be noted that the felly 1 is provided with a depression 11 which is adapted to receive a bolt 12. The bolt 12 is provided 90 with a non-circular head 13 and a non-circular nut 14. The bolt and nut have conical-shaped portions 15 and 16. The sides 17 and 18 have conical-shaped openings 19 and 20 therein in which the conical portions 15 and 16 are rotatably disposed. This construction permits the bolt 12 to be rotated, yet at the same time prevents longitudinal movement of the bolt with respect to the felly 1.

The locking plate 9 has a depending lug 21 which is provided with a threaded bore 22

through which the bolt 12 extends. It will therefore be seen that when the bolt 12 is rotated, it will move the locking plate 9 with respect to the felly 1. In Figures 1 and 3 I have shown the side 3 as being provided with an opening 23 through which the locking plate 9 is adapted to slide. The side 2, however, is cut away as at 24, (see Figure 1) so as to permit the movement of the locking plate 9 with respect to the felly 1. In the present form of the device the locking plate 9 is rectangular in shape and has two outwardly extending ribs 25 which are inclined with respect to the axis of the bolt 12, (see Figure 1). The ribs 25 provide a channel 26 in which a projection 28 carried by the rim 8, is adapted to be received.

The projection 28 is punched out of the inner side of the rim 8 and is provided with tapered sides 29, which permit the projection to be readily received in the channel 26. The cam sides 29 are shaped so as to permit the rim to be formed by dies. The projection 28 is turned so as to have its side 30 disposed parallel with the inner wall of one of the ribs 25. It will also be noted that the projection 28 does not contact with both of the inner walls of the ribs 25. This permits a movement of the locking plate with respect to the projection 28 for a purpose hereinafter described.

It will be noted that when the locking plate 9 is moved, it will move the projection 28 laterally so as to move the rim 8 into locking position. This movement is positive, since the ribs 25 engage with the projection 28 and move the projection. It will be noted that the locking plate 9 has the channel 26 thereof provided with an inclined portion 31. The inner side of the projection 28 is moved into contact with the inclined portion 31 by a means herein-after described, and when the projection 28 so engages with the inclined portion it will be moved away from the felly 1 so as to cause the rim to bind to the felly. The projection 28 rotates the rim slightly with respect to the felly 1 but does not prevent lateral movement of the rim with respect to the felly.

The means for preventing lateral movement of the rim with respect to the felly consists of the projections 10 and cam-shaped portions 6 and 7 of the felly. Figure 4 shows the projection 10 as being provided with an inclined surface 32. Figure 6 shows how the beveled side 32 contacts with the inclined portion 6 and Fig. 4 shows the portion 6 contacted by the projection 10 as being inclined at 33. The side 32 of the projection 10 and the portion 33 of the inclined surface 6 coat with each other so as to cause the projection 10 to be moved inwardly in the direction indicated by the arrow α and also radially from the felly 1

so as to cause the rim to bind with the felly. As heretofore stated, the projections are disposed about the rim and therefore bind the rim to the felly at various points about the felly so as to make a rigid connection between the rim and felly. In addition to the contacting of the surfaces 32 and 33 the rim 8 also bears against the inclined surface 7. It should be noted that the surface 7 contacts with the rim 8 throughout its entire circumference, thus providing a large supporting area for the rim. The movement of the projection 10 in the direction of the arrow α causes the portion 34 of the rim 8 to contact with the inclined surface 7. The inclined surface causes the rim to be moved slightly away from the felly so as to bind the rim to the felly and prevent movement thereof with respect to the felly.

The valve of the tire (not shown) is first inserted in the opening therefor in the felly and then the rim is swung so as to dispose the rim on the felly. The projection 28 is disposed diametrically opposite from the valve so as to permit the rim to be readily applied to the felly. The projection 28 and the projections 10 are aligned with the channel 26 and the recesses 37 respectively when the valve is inserted in the opening therefor in the felly. This permits the operator to swing the rim into place. The operator then rotates the bolt 12 by means of a wrench, whereupon the locking plate 9 will move the projection 28 circumferentially to cause the projections 10 to engage with the surface 6 and thus wedge the rim to the felly. The rim and felly have been designed so as to consist of a number of inclined surfaces which engage with each other so as to wedge the rim to the felly when the plate 9 is moved.

When releasing the rim the bolt 12 is rotated in the opposite direction and causes the projection 28 to move the rim so as to align the projections 10 with the recesses 37. As heretofore stated, the sides of the projection 28 do not contact with both sides of the channel 26. There is therefore no tendency for the projection to become locked in the channel. In case the side 30 should adhere to the wall of the rib 25, a slight tap upon the rim with a hammer or other tool will release the projection and permit the plate to move the projection. In this way the rim may be readily released from the felly even though the rim has been rigidly secured to the felly for a long time.

The weight of the rim with the tire on it is so great as to render the mounting of the rim on the felly quite difficult if it were necessary to push the rim onto the felly and at the same time turn it to cause the usual wedging action which forces the rim into position, as set forth in my above mentioned application. But this weight becomes

of great assistance in the present case for the recesses formed by cutting away the flange 6 of the felly in order to admit the projections 10 permit the free entrance of these projections.

When the rim is lifted onto the wheel, and the tire tube valve stem is inserted in the proper hole therefor in the felly in the usual manner, the rim and tire thereon may 10 be swung away from the felly and then violently swung back against the felly. The projections 10 enter their recesses without meeting any obstructions but the projection 28 contacts with the inclined shoulder 25 15 (on the right side of the lock plate in Fig. 1). As this lock plate can be properly positioned by means of the bolt 12, this engagement takes place just before the rim engages the rear flange on the felly at 7. 20 This forcible engagement of the projection 28 with the inclined shoulder forces the rim to slide around circumferentially on the felly to such an extent that the projections 10 will extend back of the inclined 25 shoulders 33 (Figs. 4 and 5) sufficiently to hold the rim in position on the felly. It is then merely necessary to turn the bolt 12 to pull the lock plate outward, which results in all the projections 10 riding up on 30 the inclined surfaces 33 and the rim being locked in position.

This initial kick causing the partial rotation of the tire following the slam of the rim against the felly is of great importance 35 for the changing of this rim is thereby rendered as simple and easy as that of the present demountable rim. If the rim were given no initial rotation to bring the projections 10 into operative position to hold 40 the rim on the felly, the inclined shoulder on the locking plate, when pulled out against the projections 28, would merely push the rim off the felly. But when such movement is prevented by this operative engagement 45 of the projections 10, the rim is forced to slide around the felly. As only a single locking bolt is necessary in the present construction, the time required to change rims is materially reduced and the cost of construction correspondingly diminished.

The depression 11 permits the felly to use a rim which is of special construction. The rim is shown in Figure 3 as being 50 provided with a supporting surface 38 for the outer casing, and a supporting surface 39 for the inner tube. In this type of rim, when the tire is deflated, the outer casing may be forced down into contact with the surfaces 39 and thereby permit the outer casing to 55 bulge at one point so as to free the outer casing from the rim at this point, and allow it to be removed from the rim. It is 60 obvious that the felly may support the standard rim with but slight alterations. 65 The arrangement of the contacting surfaces

in the rim and felly is such as to provide a device in which the rim will bind with the felly even though there is a slight imperfection in the parts, and even after the rim and felly have become slightly worn 70 through use. The surfaces 33 (see Figure 4) are in reality double cam surfaces, which not only move the rim laterally with respect to the felly 1 but also radially.

In Figure 7 I have shown a modified form 75 of the device which is identical with the preferred form except that it is adapted to be used with disc wheels. In this Figure I have shown a disc wheel 40 which has a locking plate actuating bolt 41 rotatably 80 carried by the disc 40. The locking plate 42 operates in the same manner as the plate 9 and locks the rim 8 to the disc wheel in the same manner as is done in the preferred form of the device. The disc wheel 40 is 85 fashioned into a cylindrical portion 43 which is similar to the cylindrical portion 1 (see Figure 6) and is also provided with a cam-shaped surface 44 which is similar to the surface 7 (see Figure 6). The operation of this form of the device is identical to the preferred form and therefore needs no further description.

I claim:

1. In a wheel construction, a felly having 95 recesses at right angles to one side at its periphery and inclined surfaces adjacent thereto, a rim having projections adapted to freely enter said recesses and provided with inclined surfaces adapted to engage the inclined surfaces on the felly, an inclined member mounted in the felly and adapted to be engaged by another projection on the rim when the rim is swung against the felly to carry the first named 100 projections into said recesses, the engagement of said last named projection with the inclined member on the felly after the first named projections have entered their recesses causing the rim to turn an initial 105 distance on the felly, and means to move said inclined member transversely of the face of the felly to cause further turning of the rim on the felly and operative engagement of the first mentioned projections 110 with the adjacent inclined surfaces on the felly to force the rim into final position on the felly.

2. In a wheel construction, a felly having 120 recesses at right angles to one side at its periphery and inclined surfaces adjacent thereto, a rim having projections adapted to freely enter said recesses and provided with inclined surfaces adapted to engage 125 the inclined surfaces on the felly, an inclined member mounted in the felly and adapted to be engaged by another projection on the rim when the rim is swung against the felly to carry the first named 130 projections into said recesses, the engage-

ment of said last named projection with the inclined member on the felly after the first named projections have entered their recesses causing the rim to turn an initial distance on the felly, means to move said inclined member transversely of the face of the felly to cause further turning of the rim on the felly and operative engagement of the first mentioned projections with the

adjacent inclined surfaces on the felly to 10 force the rim into final position on the felly, and a second inclined member attached to the first and movable therewith and adapted to engage the last named projection to turn the rim in the opposite direction to re- 15 lease it.

SAMUEL KAPLAN.
